UNITED STATES PATENT OFFICE

2,635,017

RAILWAY JOURNAL LUBRICATOR PUMP

James J. Hennessy, Chambersburg, Pa., assignor
to Hennessy Lubricator Company, Inc., Cham-
bersburg, Pa., a corporation of Delaware

Application October 5, 1949, Serial No. 119,661

15 Claims. (Cl. 308—84)

1

The invention relates to railway journal lubri-
cators in which a mechanical pump is actuated
by the longitudinal play of the journal in the
journal box.

In this type of lubricator, the stroke of the
pump piston may be effected by levers between
the pump and the journal actuated by the axial
movement of the journal.

One object of the invention is to secure an ef-
fective arrangement in which the relative lengths
of the levers and the resulting stroke of the pis-
ton may be arranged as desired notwithstanding
the restricted space to which the pump and its
levers must be confined.

Another object is to facilitate the insertion of
the pump through the usual opening in the end
of the box into a position between the journal
and the bottom of the journal box, and the re-
verse movement of the pump from beneath the
journal. The attainment of this object is facili-
tated by constructing the pump body of a plu-
rality of sections which may be aligned with each
other when the pump is in operating position and
may be inclined relative to each other when the
pump is being inserted into or withdrawn from
its operating position. An associated detail ob-
ject is the provision of effective lubricant passag-
eways through the pump body which will accom-
modate the inclination of the parts as indicated.

One form of a generally similar lubricator
pump is shown in Patent 2,331,835, issued Octo-
ber 12, 1943, to the present inventor, in which a
pair of cylinders extend longitudinally of the box
and adjacent the longitudinal center line of the
box and are fitted with pistons, each actuated by
a lever extending from the piston towards the
adjacent side of the box and fulcrumed, between
its ends, on the pump body. The overall length of
each lever is limited to less than one-half the
width of the box and the length of the piston
movement is restricted since the width of the
pump body, on which the lever is fulcrumed,
must be limited to accommodate the insertion and
removal of the pump.

A detail object of the present invention is to
provide a plurality of levers each having an over-
all length corresponding to the width of the pump
body or, at least, not limited to the distance be-
tween the center of the pump and an adjacent
side of the box, as in the above-mentioned patent.

2

The above objects and other detail objects as
will be referred to below are attained by the pres-
ent invention which contemplates a cylinder and
piston near each side of the pump body and an
actuating lever for each piston which extends
from the piston transversely of the body towards
the opposite side of the body and is fulcrumed
on the pump body near the end of the lever re-
mote from the associated piston and is acted
upon at a point close to its fulcrum by another
lever fulcrumed on the pump body and actuated
by the end of the journal.

In the accompanying drawings illustrating a
selected embodiment of the invention:

15 Figure 1 is a longitudinal vertical section
through the lower portion of a journal box
mounted on a journal and to which the present
lubricating device, including a suitable distributor,
has been applied. The section is taken along the
line 1—1 of Figure 2.

20 Figure 2 is a vertical transverse section through
the box and looking at the forward end of the
lubricator.

25 Figure 3 is a top view of the pump, a portion
being sectioned horizontally to better illustrate
the construction.

Figure 4 is a detail vertical longitudinal section
taken on the line 4—4 of Figure 3.

30 Figure 5 is a detail vertical transverse section
taken on the line 5—5 of Figure 3.

Figure 6 is a diagrammatic view showing the
relative position of parts of the pump body dur-
ing insertion into the box and removal from the
box.

35 The journal J mounts the usual bearing and
wedge (not shown) upon which the journal box
is carried and the latter has upright side walls 1,
a bottom wall 2 merging with the side walls and
with the box front wall 3 which has the usual
opening 4 provided with a lid (not shown). The
box rear wall 5 has the usual pocket 6 and is
equipped with a suitable dust and oil guard G.
All of the above elements are of familiar construc-
tion and in themselves do not constitute the pres-
ent invention.

40 The lubricating device consists generally of two
units; a pump unit 7 and a distributor unit 8.
The distributor unit forms the subject of a sepa-
rate application for patent filed by me August 3,
50 1949, Serial No. 108,325. The pump unit includes

a body section 9, an intermediate section 10 and an inner discharge section 11.

Body 9 mounts the operating levers 12 and 13 and has spaced parallel bores 14 forming the pump cylinders. Intermediate section 10 has passageways 15 leading from cylinders 10 to intake ports 16 and to inclined conduits 17 which meet at 18 and connect with a common discharge port 19 leading through the rear face of section 10. Passageways 15 and 17 are provided with check valves 20 and 21 which function as described below.

Each check valve 21 is housed in a cage 39 fitted into a recess in section 10. Check valves 21 and 20 are restricted in their movement by the apertured disc 39a in cage 39 (Figure 5).

Inner section 11 includes a single shouldered bore 22 leading to an upwardly extending port 23 having a semi-spherical upwardly facing terminal 24 which supports the lower end of a conduit 25 leading to the pad 26 forming a part of the distributor which is the subject of the above-mentioned application. Body 9 and section 10 are free to angle then relative to each other and are held yieldingly in the position shown in Figure 4 by coil springs 27 (Figures 5, 6), received in holes in body 9 and section 10. Pins 28, projecting from the face of section 10, are received in holes 29 in body 9 and cooperate with springs 27 to position the parts relative to each other when in the position shown in Figure 4.

Ears 30 project from the right hand face of section 10 and receive between them lugs 31 on the corresponding end of discharge section 11. Pins 32, extending through ears 30 and lugs 31, pivotally assemble the two sections.

Telescoping sleeves 33 and 34 are slidable one within the other and are received in the left hand portion of bore 22 in section 11 and are yieldingly thrust outwardly by a coil spring 35. The right hand end of sleeve 34 is seated against a shoulder in bore 22 and the left hand end of sleeve 33 is seated against the discharge port 19 in section 10.

Pistons 36 in cylinders 14 are thrust to the left by springs 37 and each is moved inwardly against the thrust of its spring by a compound lever arrangement comprising a lever 12, inclined to the horizontal and fulcrumed at 38 on lateral projections 9a on body 9, and an upright lever 13 consisting of a rod, the lower end of which 13a is bent at right angles and inserted into a recess in body 9 to form a fulcrum for the lever. The upper end of lever 13 has a contact terminal 40 for engaging the outer end of journal J by which the lever is actuated as the journal moves to the left. During such movement it moves the adjacent end of the associated lever 12 to the left and the opposite end of lever 12 acting through a strut 41 moves piston 36 inwardly against the thrust of spring 37.

Upon each outward movement of the pump sections, oil at the bottom of the box is drawn in through ports 16 past check valves 20 and upon inward movement of the pistons, oil is discharged past check valves 21 into conduits 17 and port 19 into telescoping sleeves 33, 34, bore 22, port 23 and conduit 25 to distributor 26. Lugs 45 on projections 9a limit the movement of levers 13 and thereby prevent the levers falling over when the pump is being applied to or removed from its operating position in the box.

The compound leverage arrangement makes it possible to locate the fulcrums of the journal-engaging levers 13 adjacent to the box bottom

wall. Hence the pump body may be made shallow and its projection outwardly of the plane of the end of the journal may be minimized. Each lever 12 is as long as may be desired to effect satisfactory leverage. Any desired reciprocal movement of the pistons may be obtained by shifting the fulcrums for levers 12 and the change in the lever arms will not require any increase in the depth, width or length of the pump body.

The crossed lever and compound lever arrangement positioned outwardly of the end of the journal facilitates provision of any desired piston movement to meet different journal movements, different densities of oil and other conditions affecting the pumping of an adequate supply of oil to the journal.

The underside of the pump body is elevated from box bottom wall 2 by rib-like elements 42 to provide clearance for the flow of oil to the pump intakes and screens 43 prevent dirt and other foreign matter from entering the intake.

A U-shaped holding plate 44 is secured to the box preferably by welding and fits around the main portion of the pump body and has recesses to receive body lugs 9a. Plate 44 positions the pump body in the box so that it is not shifted by the play of the journal.

By constructing the pump in three sections 9, 10, and 11, assembled so that they may angle relative to each other as shown in Figure 6, it is possible for the pump unit to be readily inserted and removed through the restricted space between the lower portion of the journal and the outwardly and upwardly curved wall 2, 3 of the box. Making intermediate section 10 separate from body section 9 and discharge section 11 facilitates the boring of the cylinders and the drilling of passageways and the provision of check valves therein, leading from the intakes to the cylinders and from the cylinders to the common discharge conduit.

The details of construction facilitate the manufacture of the pump and the assembly makes possible the use of the pump in relatively small journal boxes and avoids the necessity of jacking up the box, removing the journal bearing and wedge and then dropping the box onto the journal, as has been required in some previous lubricating devices of the same general nature.

The details of the invention may be varied substantially without departing from the spirit of the invention and the exclusive use of those modifications coming within the scope of the claims is contemplated.

What is claimed is:

1. In a pump for a railway axle box journal lubricator, a pump body having a cylinder near one side of the body, a piston in said cylinder, a lever extending transversely of said piston towards the opposite side of the pump body and fulcrumed between its ends on said body and having an end actuating said piston, and a lever pivoted to said body and acting on the other end of said first-mentioned lever and extending upwardly therefrom and having an upper end arranged to oppose the end of a journal to which the pump and associated lubricator is applied.

2. In a railway axle box journal lubricator pump, a pump body, a cylinder at one side of the body, a piston in said cylinder, a lever for actuating said piston extending transversely of said body and being fulcrumed thereon at the opposite side of said body, and a lever pivoted at one end to said body and acting on said first-

mentioned lever near its fulcrum and having its other end spaced above the body and opposing the end of a journal extending over the pump.

3. In a railway axle box journal lubricator pump, a pump body having a cylinder spaced transversely from the longitudinal center line of said body, a piston in said cylinder, a lever with one end cooperating with said piston extending transversely of the body across said center line and fulcrumed near its other end on said body, a substantially upright lever pivoted at its lower end to said body and acting on the latter-mentioned end of said first-mentioned lever with its upper end disposed to engage the end of a journal extending over the pump.

4. In a railway axle box journal lubricator pump, a pump body, spaced parallel cylinders with pistons, individual levers for actuating said pistons, each lever extending from the associated piston transversely of the body and beyond the opposite piston, and individual upright levers pivoted to said body and operatively associated with said first-mentioned levers respectively and disposed to engage the end of a journal with which the pump is associated.

5. In a railway axle box journal lubricator pump, a pump body having a pair of spaced parallel pump cylinders positioned near opposite sides of the pump body, pistons in said cylinders, means for operating each of said pistons by the longitudinal play of the journal to which the pump is applied, said means comprising a lever with one end actuating the pistons at one side of said body and extending transversely of the body and fulcrumed near its other end at the opposite side of said body, and a lever pivoted near one end of the latter-mentioned side of said body and acting on the fulcrumed end of said lever and having its other end above said body and arranged to oppose the end of a journal to which the pump is applied.

6. In a railway axle box journal lubricator pump, a pair of spaced parallel cylinders with pistons at substantially the same level, operating levers for said pistons extending transversely of the same and inclined from the horizontal, each lever having one end operatively associated with a piston and extending therefrom over the axis of the other piston and beyond the same, and substantially upright levers fulcrumed to the body and operatively associated with said first-mentioned lever with their upper ends disposed to engage the end of a journal to which the pump is applied.

7. In a railway axle box journal lubricator pump, a pair of spaced parallel cylinders with pistons at substantially the same level, operating levers for said pistons extending transversely of the same and inclined from the horizontal, each lever having one end operatively associated with a piston and fulcrumed to the body adjacent the other piston and extending over the axis of the latter-mentioned piston and beyond the same, and individual levers fulcrumed to the body adjacent the ends of the first-mentioned levers and engaging the same and extending upwardly therefrom with their upper ends disposed to engage the end of a journal to which the pump is applied.

8. In a railway axle box journal lubricator pump, a pair of sections hinged together, aligned lubricant passages in said sections with their axes extending transversely of the sections hinge axis, a socket at the end of the passage in at least one of said sections and opposing the other

passage, and a tubular device slidably received in said other passage with an end projected therefrom and seated in said socket.

9. In a railway axle box journal lubricator pump, a pair of sections hinged together, aligned lubricant passages in said sections with their axes extending transversely of the sections hinge axis, a device slidably fitting in at least one of said passages and comprising telescoping sleeves, yielding means thrusting said sleeves apart, and seats in said passages for the outer ends of said sleeves.

10. A pump structure as described in claim 9 in which the major portions of the sections have substantially planar opposing faces and the device normally is positioned substantially wholly within one of said passages with a part projecting therefrom and having a ball-like terminal, and the seat in the other section for said terminal comprises a spherical socket for said terminal positioned immediately adjacent the opposing faces of said sections.

11. In a railway axle box journal lubricator pump, a body section comprising spaced parallel cylinders each provided with a piston and having an opening through an upright face of the section adjacent the inner ends of the cylinders, an intermediate section having passageways aligned with said openings, a central outlet port and transverse conduits connecting said port and passageways, there being spaced inlet ports through the bottom of the intermediate section adjacent to said passageways, and an elongated narrow section having a central conduit aligned with said outlet port and terminating in an upwardly facing discharge terminal remote from said intermediate section, and means connecting said intermediate section to each of the other sections so that they may pivot relative to the intermediate section about horizontal axes extending transversely of the cylinders and said central conduit.

12. A structure as described in claim 11 which includes piston actuating levers extending transversely of the body section and fulcrumed thereon and crossing each other, and operating levers fulcrumed on the body section and extending upwardly therefrom, and means on said body section holding said operating levers in substantially upright positions.

13. In a railway axle box journal lubricator pump, a body unit comprising spaced parallel cylinders, pistons in said cylinder and piston operating levers on said body, a distributor-mounting unit having a central conduit and an upwardly facing terminal at the inner end thereof, and an intermediate unit with lubricant intake and discharge ports, with associated check valves and a common passage connected thereto and to said cylinders and said conduit, said body unit being pivotally assembled to swing vertically relative to each other transversely of the cylinder axes.

14. In a lubricator structure for insertion through the end of an ordinary railway journal box into the space below the journal upon which the box is mounted, a plurality of sections arranged end to end, means holding said sections assembled and providing for their tilting on each other about axes extending transversely of the length of the device, there being aligned elongated lubricant passages in adjacent sections, an oil conducting device received in at least one of said passages, a bearing associated with the passage in the other section for the outer end of said de-

vice, said device comprising telescoping sleeves and means thrusting said sleeves apart.

15. In a railway axle box journal lubricator pump, a pump body, spaced parallel cylinders and pistons near the sides of the body, individual levers for actuating said pistons, each lever oscillating in a plane inclined to the horizontal, the levers crossing each other near the longitudinal center of the body, one in front of the other, a connection between one end of each lever and an associated piston, a secondary lever fulcrumed to the body adjacent the other end of

each first-mentioned lever and extending therefrom upwardly to contact the end of a journal to which the device is applied.

JAMES J. HENNESSY.
